US0D1027182S

(12) **United States Design Patent** (10) **Patent No.:** **US D1,027,182 S**
(45) **Date of Patent:** **** May 14, 2024**

(54) **HEART MONITOR**

(71) Applicants: **Interface Technology (ChengDu) Co., Ltd.**, Chengdu (CN); **INTERFACE OPTOELECTRONICS (SHENZHEN) CO., LTD.**, Shenzhen (CN); **GENERAL INTERFACE SOLUTION LIMITED**, Zhunan (TW)

(72) Inventors: **Chun-Ming Cheng**, Xinzhu (TW); **Chih-Lin Liao**, Zhunan (TW); **Yi-Chia Chiu**, Zhunan (TW); **Chun-Ta Chen**, Chengdu (CN); **Po-Lun Chen**, Chengdu (CN)

(73) Assignees: **Interface Technology (ChengDu) Co., Ltd.**, Chengdu (CN); **INTERFACE OPTOELECTRONICS (SHENZHEN) CO., LTD.**, Shenzhen (CN); **GENERAL INTERFACE SOLUTION LIMITED**, Zhunan (TW)

(**) Term: **15 Years**

(21) Appl. No.: **29/849,777**

(22) Filed: **Aug. 15, 2022**

(30) **Foreign Application Priority Data**

Jul. 19, 2022 (CN) 202230459215.5

(57) **CLAIM**

The ornamental design for a heart monitor, as shown and described.

DESCRIPTION

FIG. 1 is a front perspective view of a heart monitor showing our design.

FIG. 2 is a rear perspective view of the heart monitor in FIG. 1.

FIG. 3 is a front elevation view of the heart monitor in FIG. 1.

FIG. 4 is a rear elevation view of the heart monitor in FIG. 1.

FIG. 5 is a left side elevation view of the heart monitor in FIG. 1.

FIG. 6 is a right side elevation view of the heart monitor in FIG. 1.

FIG. 7 is a top plan view of the heart monitor in FIG. 1; and, FIG. 8 is a bottom plan view of the heart monitor in FIG. 1. The broken lines in the drawings are employed to show unclaimed portions of the heart monitor, and form no part of the claimed design.

1 Claim, 8 Drawing Sheets
